UNITED STATES PATENT OFFICE.

GEORGE L. PIERCE, OF MANCHESTER, NEW HAMPSHIRE.

RING-HOLDER FOR SPINNING AND TWISTING RINGS.

No. 830,452.

Specification of Letters Patent.

Patented Sept. 4, 1906.

Application filed April 8, 1905. Serial No. 254,439.

To all whom it may concern:

Be it known that I, GEORGE L. PIERCE, a citizen of the United States, residing at Manchester, in the county of Hillsboro and State 5 of New Hampshire, have invented an Improvement in Ring-Holders for Spinning and Twisting Rings, of which the following description, in connection with the accompanying drawings, is a specification, like characters 10 on the drawings representing like parts.

This invention has for its object the production of a novel ring-holding means whereby a ring of one size may be readily substituted for a ring of another size, according to 15 the count of the yarn to be spun or twisted.

A ring-holding means comprising my invention includes a rail-plate and a detachable ring sustaining or receiving device that sustains the ring about which the traveler or 20 yarn-controller revolves. Each sustaining or receiving device is provided with a ring of the desired size, according to the count of yarn to be spun or twisted.

The rail-plate has a central opening of a 25 size sufficient for the largest ring to be used and the bobbin to be filled, according to the diameter of the ring which is to be fitted thereinto.

The base of the ring sustaining or receiving 30 device is of the same size and shape whatever the diameter of the ring, and it may fit in like manner the rail-plate, and said sustaining or receiving device is prevented from rotation on and is locked to the rail-plate and is thus 35 prevented from being moved vertically and from being detached from the ring-plate except by overcoming the force of the means employed to effect the locking of the ring sustaining and receiving device to the ring- 40 plate.

Figure 1 in side elevation represents a portion of a ring-rail with my novel ring-holding means applied thereto. Fig. 2 is a plan view of Fig. 1 with the ring sustaining or receiving 45 device or plate partially broken out. Fig. 3 is a section on the line 3, Fig. 2. Fig. 4 is a plan view of the rail-plate detached; and Fig. 5 is a plan view of the ring sustaining or receiving device or plate detached, the dotted 50 lines therein showing different sizes of openings that may be made in the said device or plate for rings of different diameter.

Referring to the drawings, A represents 55 part of a ring-rail, on which is shown as resting about one of the usual spindle-openings therein a rail-plate a, shown as composed of

sheet metal and provided with two lugs or uprights a' a'', said plate having two like slots a³ for the reception of the fastening-screws, that enter the ring-rail and confine the rail- 60 plate about the spindle-openings.

The central hole in the rail-plate is of a size sufficient to receive a mass of yarn of the greatest diameter, which is to be wound on the bobbin to be revolved in the usual opening in the ring-rail. The lug or upright a' 65 acts as a positioning device for the ring sustaining or receiving plate b, to be described, while the lug or upright a'' forms part of a locking device, said lug or upright having, as 70 herein shown, a projection a'', which extends inwardly therefrom, said projection being shown as formed by a prick-punch.

The ring sustaining or receiving plate b, (shown detached in Fig. 5,) that receives the 75 ring d or device that guides and controls the traveler d' in its movement, is also represented as cut from sheet metal and is notched, as shown, at c to embrace the lug or upright a'' of the ring-plate to thereby position the ring 80 d, of whatever diameter, centrally with relation to the spindle to be used. Said sustaining or receiving plate is provided opposite said notch with a lug c', having, as shown, a 85 recess, that may be formed by a prick-punch, to be entered by the projection a'', referred to, of the lug or upright a', said projection and recess constituting one form of locking means for preventing the lifting of the ring sustaining or receiving plate from the rail- 90 plate except when the friction of said two parts is overcome, as it may be by inserting a piece of metal in the small opening c'. (See Fig. 1.)

The exterior contour of the ring sustaining 95 or receiving plate may and is supposed to be the same in shape for all sizes of rings; but the central hole (see Fig. 5) in said plate will vary in diameter in accordance with the diameter of the ring to be sustained thereby. 100

The plate b has, as shown, three upturned ears f, against which one of the flanges, herein the lower flange of the double ring, is engaged, said ring being forced into engagement with said ears, so that they hold the 105 ring firmly.

It will be obvious that if a ring of smaller diameter is to be held in the plate b a ring, for instance, the diameter of which corresponds to the dotted circular lines in Fig. 5, 110 then the width of the plate b from its exterior edge 6 to the inner edge 5 of the opening will

vary; but the ears *f* in each different plate will be at the same distance from the inner edge 5.

The ring sustaining or receiving plate has 5 two open notches 2, in which rests the heads of the screws employed to fasten the rail-plate firmly to the ring-rail.

Believing that I am the first to mount a ring in a ring receiving or sustaining plate 10 and thereafter apply said plate to the surface of a rail-plate permanently attached to a ring-rail and to lock the ring-receiving plate and the rail-plate together, I desire to cover this 15 class of ring-holding means broadly irrespec- tive of the particular construction shown, al- though the parts in which I have herein em- bodied my invention are the best known to me and are eminently practical.

Having fully described my invention, what 20 I claim as new, and desire to secure by Letters Patent, is—

1. A ring-holder comprising a rail-plate adapted to be confined to the top of a ring-rail and having a positioning device and a 25 locking device, and a ring sustaining or receiving plate having a notch, and a device co- acting with the locking member of the rail- plate.

2. A ring-holder comprising a rail-plate 30 adapted to be confined to the top of a ring-rail and having a positioning device and a locking device, and a ring sustaining or receiving plate having a notch, and a device co- acting with the locking member of the rail- 35 plate, said ring sustaining or receiving plate having ears combined with a ring forced into position between and held by said ears.

3. A sheet-metal rail-plate having one member of a positioning device and one mem-

ber of a locking device, combined with a 40 sheet-metal ring-receiver having a coacting ring-positioning device and a coacting locking device to operate substantially as de- scribed.

4. A sheet-metal rail-plate having two 45 lugs or uprights, combined with a ring sus- taining or receiving plate having a notch and an upright, the notch of the latter plate embrac- 50 ing one of the uprights of said rail-plate, the other upright of the rail-plate and the up- right of the ring sustaining or receiving plate being adapted to engage one the other fric- tionally to hold the ring sustaining or receiv- ing plate seated operatively upon the rail- plate.

5. The combination with a ring-receiver having ears, of a double-raced ring forced 60 into engagement with ears of said receiver, said receiver having a notch and also pro- vided with one member of a locking device, 65 and a rail-plate adapted to be secured to a ring-rail and having an upright that is en- gaged by the notch of the receiver, said rail- plate having a part forming the second mem- ber of a locking device.

6. In a ring-holder, a plate having ears to 70 engage the flange of and hold a ring, and resilient means between which the plate may be inserted and snapped to confine the plate in working position.

In testimony whereof I have signed my name to this specification in the presence of two subscribing witnesses.

GEORGE L. PIERCE.
